PLATFORM SHOE SOLE

Beth Levine, 59 W. 12th St., New York, N.Y.

Filed Dec. 6, 1962, Ser. No. 72,741

Term of patent 14 years

(Cl. D7—5)

FIG. 1

FIG. 2

FIG. 3

FIG. 5

I claim:

The ornamental design for a platform shoe sole, substantially as shown.
